DESIGN FOR A SHOE

Newton Elkin, Philadelphia, Pa.

Application March 30, 1934, Serial No. 51,265

Term of patent 3½ years

To all whom it may concern:

Be it known that I, NEWTON ELKIN, a citizen of the United States, residing in Philadelphia, in the county of Philadelphia, and State of Pennsylvania, have invented a new, original, and ornamental Design for a Shoe, of which the following is a specification, reference being had to the accompanying drawing, forming part thereof.

I claim:

The ornamental design for a shoe, as shown.

NEWTON ELKIN.
